JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FEELER-LOOM.

1,361,897.

Specification of Letters Patent.

Patented Dec. 14, 1920.

Application filed August 3, 1916. Serial No. 112,921.

To all whom it may concern:

Be it known that I, JONAS NORTHRUP, a citizen of the United States, residing at Hopedale, in the county of Worcester and 5 State of Massachusetts, have invented certain new and useful Improvements in Feeler-Looms; and I do hereby declare the following to be a full, clear, and exact description of the invention, such as will enable others skilled in the art to which it 10 appertains to make and use the same.

The present invention relates to an improvement in feeler looms.

Feeler looms are a type of weft replenishing looms wherein the operation of the weft replenishing mechanism is initiated by a filling feeler mechanism when the latter detects and indicates critical or predetermined exhaustion of the filling in the active 15 shuttle. Such looms are commonly provided with one or more filling detectors which operate to cause loom stoppage on the detection of filling absence, which may be caused either by the breakage of the filling or by 20 its complete exhaustion. In the most usual construction of feeler loom, especially in the Northrop type of loom, the weft replenishing mechanism is located on one side 25 of the loom and the filling feeler mechanism is located on the opposite side, with a filling 30 detector situated adjacent the filling feeler mechanism. With the filling detector in this situation, the purpose of a feeler loom, namely, the weaving of as nearly perfect 35 cloth as is possible, is sometimes frustrated because of the occasional occurrence of "trailing" filling ends. A trailing filling end is present when the filling breaks at such a distance from the shuttle eye that 40 when the shuttle is boxed at the filling feeler side of the loom, the filling end extends from the shuttle eye (which is then nearer the adjacent selvage) sufficiently far toward 45 the shed, or even into the shed, to cause the fork of the filling detector to be tilted in the same manner as though an intact filling extended through the length of the shed. The occurrence of a trailing filling end results in a mispick, that is, in the complete or in the 50 partial absence of a pick in a shed. Mispicks in the cloth impair its quality. A trailing filling end is also present when, after the filling feeler mechanism has indicated predetermined exhaustion of filling in 55 the shuttle, the weft replenishing mecha-

nism is for some reason, as for instance, because of the improper boxing of the shuttle, prevented from operating on the next beat-up of the lay. As feeler looms are usually constructed, the non-operation of the weft 60 replenishing mechanism does not prevent the operation of the "feeler thread parter," which acts to sever, relatively near the shuttle, the filling end extending from the selvage to the shuttle eye when the shuttle is 65 boxed at the weft replenishing side of the loom on the next beat-up after the indication of critical exhaustion of filling. Consequently, the shuttle with the severed filling end is picked to the opposite side of the 70 loom, and this filling end, extending as it usually does a few inches into the shed, prevents the filling detector from stopping the loom and is woven into the cloth, causing a mispick and the resulting blemish as de- 75 scribed before. If, as is sometimes the case, the cause of the non-operation of the weft replenishing mechanism persists for several beats of the lay, and there is sufficient filling in the shuttle to last for several picks across 80 the shed, the mispicks resulting from the non-operation of the weft replenishing mechanism will develop into a "thin place,"—a far more serious blemish than a single mispick. 85

One object of the present invention is to prevent the occurrence of "trailing end" mispicks resulting from the first specified cause, by producing a feeler loom (provided with a single filling detector) in which the 90 filling detector is located adjacent the weft replenishing mechanism. The feeler loom of the present invention has provision for causing loom stoppage if after the indication of critical exhaustion of filling, the filling in the shuttle entirely exhausts during the pick from the filling feeler side of the loom to the weft replenishing side. At the same time the "false" absence of filling caused by the severing of the outgoing filling end does not result in loom stoppage. 95

To the accomplishment of this object and such others as may appear, the invention consists in the loom hereinafter described and particularly pointed out in the claims. 105

In the accompanying drawings illustrating the preferred form of the invention, Figure 1 is a side elevation of a portion of the weft replenishing side of a loom, looking from the left, showing the application 110

of the feeler thread parter and of the filling detector of the present invention thereto; Fig. 2 is a plan of the filling detector; Figs. 3 to 5 inclusive, are sectional side elevations 5 of the filling detector and associated parts, showing the positions of its members in various phases of its operation; Fig. 6 is a front elevation of a portion of the weft replenishing end of the loom showing the application thereto of the filling detector and 10 of the stop mechanism of the present invention; and Fig. 7 is a diagrammatic view showing the interrelation of the various mechanisms comprising the present invention. 15

The feeler loom to which the various mechanisms of the present invention are applied may be of any usual or preferred form. The loom, of which a portion is shown in 20 the illustrated embodiment of the invention, is provided at one side with a weft replenishing mechanism, of which the hopper containing the supply of filled bobbins is indicated at 12, and at the opposite side with 25 a filling feeler mechanism, indicated at 13, Fig. 7. The two mechanisms are operatively connected by a hollow rock or change shaft 14 which is journaled in suitable brackets and extends across the front of the loom. 30 The hollow change shaft 14 loosely embraces a stop shaft 15 (Fig. 6). When the filling in the shuttle 16 has been exhausted to a critical or predetermined extent, the filling feeler mechanism operates in the usual manner 35 to oscillate the change shaft and initiate the weft replenishing operation. Located on the same side of the loom with the weft replenishing mechanism is the feeler thread parter 17 which operates to sever relatively 40 near the selvage the outgoing filling end (which extends from the selvage to the shuttle eye) during the weft replenishing beat-up of the lay, which is the beat-up following indication of critical exhaustion of filling. The thread parter also operates to 45 sever relatively near the selvage the incoming filling end (which extends from the hopper to the selvage) during the first beat-up of the lay following replenishment. The 50 operation of the thread parter is initiated when the change shaft is oscillated by the filling feeler mechanism. Situated between the thread parter and the weft replenishing mechanism is the filling detector, indicated 55 at 18. The filling detector is connected with the stop shaft, which in turn is connected at the other side of the loom with the shipper. When the filling detector detects filling absence, it operates in the usual manner to 60 cause an oscillation of the stop shaft, by which the shipper is disconnected from its holding notch and the loom thereby stopped. Secured to the right-hand end of the stop shaft is an arm 20, on the upper end of 65 which is pivoted a stop mechanism latch 21,

which, when the shuttle is improperly boxed on the weft replenishing beat-up of the lay, is adapted to be brought into the path of a stop bunter 22 secured to the front side of the lay 23, and thereby cause an oscillation 70 of the stop shaft to stop the loom. It is thus seen that the feeler loom of the present invention has provision whereby it may be stopped whenever filling absence occurs, and whenever filling replenishment has been 75 called for by critical exhaustion of filling and the replenishing operation is prevented from taking place because of an improperly boxed shuttle. The occurrence of mis- 80 picks and thin places resulting from trailing threads is therefore prevented, since the pick may be "matched."

The thread parter mechanism of the present invention comprises a series of parter blades 17 (Fig. 1) located rearwardly of the 85 lay with their forward ends projecting through the dents of the reed 25, a little to one side of the selvage of the cloth being woven. The parter blades are adapted to coöperate with the reed dents to sever the 90 outgoing filling end during the weft replenishing beat-up of the lay, and on the succeeding beat-up of the lay to sever the incoming filling end. The thread parter of the present invention is constructed and 95 operates in substantially the same manner as the thread parting mechanism shown and described in my copending application for United States Letters Patent, Serial No. 93,216, wherein it is claimed. The parter 100 blades 17 are secured to a block 26 fastened to the inner end of a crank shaft 27. The parter blades are held raised in normal or inoperative position during regular weaving, as shown in Fig. 1, by means of a cam 28 formed on the lower side of a controller 29 pivoted on a stud 30 secured to a bracket 31 fastened to the loom frame. The cam 28 presses downwardly on the crank pin 32 of the crank shaft and thereby holds the forward ends of the parter blades elevated. The controller 29 is operatively connected 105 with a parter blade release lever 33, also pivoted on the stud 30. The forward end of the release lever 33 rests on a shoulder 34 of a latch lever 35 pivoted at 36 on the upper end of the change arm 37, which is secured at its lower end by means of the split collar 38 to the hollow change shaft 14. When critical exhaustion of filling has been 110 indicated by the filling feeler mechanism and the change arm 37 swings to the right, viewing Fig. 1, the shoulder 34 of the latch lever moves from under the forward end of the release lever 33, whereupon the latter 115 descends by force of gravity. The release lever is provided with an obliquely disposed cam slot 40 which receives a pin 41 projecting laterally from the forward end of the controller 29. When the forward end of the 120 controller 29 is lowered, the pin 41 enters the cam slot 40 and holds the release lever 33 in its lowered position. The release lever 33 is provided with a 125 cam slot 42 which receives a pin 43 projecting laterally from the forward end of the controller 29. When the forward end of the 130 controller 29 is lowered, the pin 43 enters the cam slot 42 and holds the release lever 33 in its lowered position.

release lever descends, it carries downwardly with it the forward or hook-shaped end 42 of the controller into the path of movement of a bunter 43 secured to the upper surface of 5 the shuttle box at the weft replenishing side of the lay. The engagement of the bunter 43 with the hook 42 carries the controller forward, the slot 44 formed in the rear end of the controller permitting its movement on 10 the pivot stud 30. The forward movement of the controller disengages the cam 28 from the crank pin 32 of the crank shaft 27; whereupon a spring device, indicated generally at 46, connected with the crank pin 32 15 acts to raise it and thereby depress the cutting edges 47 of the parter blades 17 toward the shuttle race 48 and in front of the filling. The continued forward movement of the lay carries the filling against the cutting edges 20 47 of the parter blades and the filling is thereby severed. As the lay beats forward and carries with it the controller by the engagement of the bunter 43 with the hook 42, the pin 41, by pressing against the upper 25 surface of the slot 40, raises the forward end of the release lever; but inasmuch as the change arm 37 does not return until after the beginning of the return beat of the lay, the forward end of the release lever 30 descends before the shoulder 34 can pass under it. This operation of the release lever is permitted by the controller which, as the lay beats back, is released from the bunter 43; and thereupon a spring (not 35 shown) returns the controller to its rearward or normal position. The return of the controller to its normal position raises the forward ends of the parter blades to permit the shuttle to make its flight across the lay. 40 The descent of the forward end of the release lever again positions the hook 42 of the controller in the path of the bunter 43, and the forward ends of the parter blades are again lowered into operative position as the 45 lay moves forward on the beat-up following the replenishing operation. The backward beat of the lay after replenishment permits the arm 37 and the latch lever 35 to return to normal position, so that, by the time the 50 forward end of the release lever is again raised, the shoulder 34 of the latch lever is permitted to swing under it. The forward end of the release lever is then held raised on the latch shoulder; the next succeeding 55 backward beat of the lay disengages the bunter 43 from the hook 42, and thereupon the spring (not shown) holds the controller rearwardly, so that thereafter the cam 28 presses downwardly on the crank pin 32 to 60 maintain the cutting edges of the parter blades elevated until the next indication of critical filling exhaustion. Thus it is seen that the thread parter operates to sever the outgoing filling end during the replenishing 65 beat-up of the lay and the incoming filling

end during the succeeding beat-up of the lay. The thread parting operation takes place about the time the warps are crossing each other for the next shedding. The reed at this time is about an inch from the fell. 70

The filling detector 18 comprises a slide 50 mounted for reciprocatory forward and backward movements in a guideway 51 secured to the breast beam 52 of the loom. Pivoted at 53 on the rearward end of the 75 slide 50 is a filling engaging fork 54 having downwardly depending tines 55 which are adapted to pass through the uprights 56 of the usual grid 57, Fig. 1. When the shuttle is boxed at the weft replenishing side of the 80 loom and there is filling present in front of the grid 57, the forward motion of the lay carries the filling against the tines 55 and thereby tilts the fork 54 upon its pivot 53, swinging the forward end or tail 58 of the 85 fork clear of the path of motion of the barb of a hook 59 pivoted at 60 on the upper end of the weft hammer 61, as the latter beats forward. If, however, the filling is not present on this beat-up of the lay, the filling 90 engaging fork is not tilted and the tail 58 of the fork remains in the path of motion of the barb of the hook 59 as the weft hammer beats forward, and, consequently, the hook 59 engages the tail of the fork and 95 through the connection of the latter with the slide 50 pushes the slide forward so that a boss 62 formed on the forward end of the slide is forced against the upper end of a stop arm 63 secured to and rising from the 100 stop shaft 15, thereby oscillating the stop shaft to stop the loom. The rearward movements of the slide 50 are limited by the engagement of the shoulder 64 formed on the forward end of the slide with an abutment 105 65 projecting upwardly from the guideway 51.

As looms are usually constructed the filling detector is arranged and adjusted so that the filling detecting operation takes place just about the time the reed reaches the fell to beat up the last laid weft. The thread parting mechanism employed in conjunction with the other structures of the present invention, operates to part the outgoing and 110 the incoming filling ends at about the time the shed is closing upon the weft thread, which is when the reed is about one inch from the fell, as described above. It is obvious, therefore, that if the filling detector 115 of the present invention were permitted to operate in the usual manner, it would detect filling absence after the thread parting mechanism had operated to part the outgoing filling end and would stop the loom 120 each time the thread parting mechanism was brought into operation, namely, each time that critical exhaustion of filling was indicated by the filling feeler mechanism. To 125 prevent this unnecessary loom stoppage, the 130

filling detector of the present invention is constructed so that it is brought into operation to detect the absence or presence of filling immediately before the thread parting mechanism is brought into operation. To this end the detector slide 50 and its guide support 51 are adjusted rearwardly to bring the tines 55 of the detector fork 54 into operative relation with the grid 57, so that if 10 the filling is present in front of the grid the fork will be tilted, before the cutting edges 47 of the parter blades are in transverse alinement with, that is, in thread parting relation with the dents of the reed 25. 15 The relation of the parts at this time is shown in Figs. 2, 3, and 4. At this time the lay is moving forward more rapidly than when it has more nearly reached its forward center. Consequently, the detector fork 54 20 is swung about its pivot very rapidly, and the momentum thus generated has a tendency to cause the fork to rebound, with the result that the tines are often forced behind the filling. Then on the next pick the filling 25 loops about the tines and the detector fork is thereby rendered inoperative. To prevent the detector fork from being rendered inoperative from this cause, it is provided with a pin 67 which depends from the fork just forward of its pivot 53. When the filling has engaged the tines 55 and tilted the detector fork about its pivot, swinging the tail 58 clear of the barb of the hook 59, the forward movement of the weft hammer 35 61 brings a crossbar 68 on the rear end of the hook 59 into engagement with the pin 67, thereby positively preventing the filling detector from rebounding or returning toward the grid (Fig. 1) until the next backward movement of the weft hammer, by 40 which time the shuttle has been picked to the opposite side of the loom and all liability of the filling looping around the tines 55 has been obviated.

45 By placing the filling detector on the weft replenishing side of the loom and providing means by virtue of which its operation is not affected by the false filling absence which results when the feeler thread parter 50 severs the outgoing filling end, the loom is stopped whenever there is a filling absence, whether or not there is a trailing filling end. This is because when the shuttle is boxed at 55 this side of the loom the shuttle eye is farther from the selvage than when the shuttle is boxed at the other side of the loom. The trailing filling end, therefore, does not extend in front of the tines of the detector fork, as would be the case if the detector 60 mechanism were located on the filling feeler side of the loom.

Having thus described the nature and scope of the present invention, what is claimed is:—

65 1. A loom having, in combination, a weft

replenishing mechanism, a filling feeler mechanism, a thread parting mechanism for severing the outgoing and incoming filling ends, and a filling detector for detecting the presence or absence of filling in the shed 70 when the shuttle is boxed at the replenishing side of the loom, said parts being constructed and arranged so that the filling detecting operation takes place on the replenishing beat-up of the lay before the severing 75 of the outgoing filling end, and the severing of the incoming filling end is performed before the next succeeding detecting operation.

2. A loom having, in combination, a weft 80 replenishing mechanism, a thread parting mechanism located on the replenishing side of the loom, and a filling detector situated between the thread parting mechanism and the weft replenishing mechanism, said parts 85 being constructed and arranged so that on the replenishing beat-up of the lay the filling detector performs its operation first.

3. A loom having, in combination, a lay, a shuttle, a weft replenishing mechanism, a 90 thread parter arranged to sever the outgoing filling end on the replenishing beat-up of the lay, and a filling detector located between the weft replenishing mechanism and the thread parter arranged to detect the 95 presence or absence of filling on the replenishing beat-up of the lay before the operation of the thread parter.

4. A loom having, in combination, a lay, a shuttle, a weft replenishing mechanism 100 and a filling feeler mechanism located on opposite sides of the loom, loom stopping means, a thread parter located on the same side of the loom with the weft replenishing mechanism arranged to sever the outgoing filling end on the replenishing beat-up of the lay, and a filling detector arranged to cause loom stoppage if there is no filling extending from the selvage to the shuttle on the replenishing beat-up of the lay before the 105 thread parter operates.

5. A loom having, in combination, a lay, a shuttle, a weft replenishing mechanism and a filling feeler mechanism located on opposite sides of the loom, loom stopping means, a thread parter arranged to sever the filling extending from the selvage to the shuttle on the next beat-up of the lay after the indication of critical exhaustion of filling, and a filling detector located between 115 the weft replenishing mechanism and the thread parter arranged to detect the presence or absence of the filling extending from the selvage to the shuttle before the operation of the thread parter, and if such filling 120 is absent to cause loom stoppage.

6. A loom having, in combination, a lay, a shuttle, a weft replenishing mechanism, a filling feeler mechanism, a thread parter arranged to sever the outgoing filling end 130

on the replenishing beat-up of the lay, and to sever the incoming filling end on the succeeding beat-up of the lay, and a filling detector arranged to detect the presence or absence of the outgoing filling end before the 5 operation of the thread parter.

7. A loom having, in combination, a lay, a shuttle, a weft replenishing mechanism, a filling feeler mechanism, a thread parter 10 arranged to sever the outgoing filling end on the replenishing beat-up of the lay, and a filling detector arranged to detect the presence or absence of filling when the shuttle is boxed on the weft replenishing side of 15 the loom, said detecting operation taking place on the replenishing beat-up of the lay before the thread parting operation.

8. A loom having, in combination, a weft replenishing mechanism, a filling feeler 20 mechanism, a thread parting mechanism for severing the outgoing filling end on the replenishing beat-up of the lay, a filling detector on the replenishing side of the loom having a fork for detecting the presence or 25 absence of filling before the thread parting operation, and means for preventing the fork from returning immediately to normal position when the outgoing filling end has been severed.

9. A loom having, in combination, a weft replenishing mechanism, a filling feeler mechanism, a thread parter arranged to be brought into operation to sever the outgoing filling end, and a filling detector arranged 35 to detect the presence or absence of filling before the operation of the parter mechanism.

10. A loom having, in combination, a lay, a weft hammer, a filling detector including 40 a fork, and means connected with the fork

arranged for engagement by the weft hammer each time the fork has been tilted by the filling to continue the tilting movement of the fork during the forward beat of the weft hammer, and to permit the fork to return to 45 normal position on the return beat of the weft hammer.

11. A loom having, in combination, a lay, a shuttle, a weft hammer, a filling detector comprising a detector slide, a filling fork 50 pivoted thereon, and a pin depending from the fork adapted to coöperate with the weft hammer on the forward beat of the latter, when the detector detects presence of filling, to tilt the fork and maintain it in raised 55 position until the return beat of the weft hammer.

12. A feeler loom having, in combination, a lay, a thread parter to sever the outgoing filling end on the replenishing beat of the lay, a filling detector comprising a fork, located on the same side of the loom with the thread parter, arranged to determine the presence or absence of filling before the operation of the thread parter, and means to prevent the return of the fork to its normal position until after the return beat of the lay has carried the filling out of the path of the return movement of the fork.

13. A loom having, in combination, a lay, 70 a weft hammer, loom stopping devices, a filling detector including a pivoted fork having provision by virtue of which it is engaged and tilted by the weft hammer on each forward beat thereof whenever filling 75 is present, and causes the operation of the loom stopping devices by movement of the weft hammer whenever the filling is absent.

JONAS NORTHRUP.
